UNITED STATES PATENT OFFICE.

EUGENE HAHN, OF PHILADELPHIA, PENNSYLVANIA.

EJECTOR.

1,420,543.

Specification of Letters Patent. Patented June 20, 1922.

Application filed October 24, 1919. Serial No. 332,949.

To all whom it may concern:

Be it known that I, EUGENE HAHN, a citizen of Hungary (having declared my intention of becoming a citizen of the United States), and a resident of Philadelphia, Pennsylvania, have invented certain Improvements in Ejectors, of which the following is a specification.

This invention relates to ejectors for ashes and similar material, and more particularly to that type of ejector in which the material is sucked into an ejector pipe and forced therethrough by means of the rapid discharge of a fluid, such as steam or compressed air, through a nozzle suitably located in the said pipe. Although ejectors of this general type are well known in the art, their application to boats, and particularly to ocean going vessels, is complicated by certain unique factors presenting problems which must be solved before the ejectors can be made suitable for this style of work. It is the adaptation of these ejectors to use in vessels, particularly vessels employed in ocean traffic, which constitutes the object of my invention.

In the attached drawings;

Fig. 1 is a side elevation of my ejector, and shows in outline a portion of the shell of the boat in which it is installed;

Fig. 2 is a plan view of the lower portion of the ejector;

Fig. 3 and Fig. 4 are perspectives of a portion of the operating rod and bracket respectively;

Fig. 5 is a side elevation of the outer end of the ejector pipe, showing the cap partially open; and

Fig. 6 is a vertical section of the outer end of the ejector pipe, showing a modified form of closure.

With reference to the drawings, 1 indicates a portion of the outer shell of a vessel, and 2 the floor of the fire-room or stoke-hole.

The ejector comprises a conveyor pipe, 3, which extends from the fire-room upwardly and through the side of the vessel above the water line. A laterally extending branch pipe, 4, joins the conveyor pipe, 3, at a point near the lower extremity thereof, said pipe 4 being apertured intermediate the ends and having a flanged intake fixture, 5, attached

above the aperture. The disposition of the ejector within the vessel is preferably such that the upper surface of the intake fitting lies flush with the floor of the stoke-hole. Seated within the aperture in the intake fixture, 5, is a lid or cover, 6, said lid fitting the aperture neatly so as to form a watertight connection when closed. Intermediate the intake hole and the outer end of the pipe 4, is located a gate valve, 7, by means of which the outer open end of the pipe may be shut off. The lower extremity of the pipe 3, is closed off, and a nozzle projects through the end closure of this pipe and into the interior of the pipe, said nozzle being connected by means of a pipe, 8, with any suitable source of fluid energy.

In the present instance, I have shown the pipe, 8, extending to the compression tank, 35, of an air compressor, 36, the use of compressed air having certain advantages over steam which will be disclosed hereinafter.

Pivoted to a lug, 9, upon the outer end of the pipe 3, is a cap, 10, adapted to lie over the end of the pipe, as shown in Fig. 1, and a lever arm, 10^a, extends upwardly from the cap, to the upper end of which arm is attached a link 11. This link, 11, establishes connection between the cap, 10, and a rod 12, to which it is pivotally secured, the rod 12 being similarly connected at its opposite end to a rod 13, which in turn is pivotally connected to an operating rod, 14, located in the stoke room. The rod 13, is pivotally attached at a point intermediate its extremities, to a bracket, 15, or to some similar suitable support.

The operating rod, 14, is supported by a slotted stand or bracket, 16, the rod resting in the slot and being free to slide therethrough. It will now be apparent that when the operating rod 14, is pushed forward longitudinally in the bracket, in the direction indicated in the drawings by the arrow, the cap, 10, will be elevated and the outer end of the pipe 3 uncovered. A notch, 17, formed in the underside of the operating rod, 14, 100 engages the bracket, 16, and so prevents the cap from dropping down over the end of the pipe, while a similar notch, 18, functions in similar manner to prevent accidental opening of the cap when closed. In Fig. 5 the 105 cap is shown partially elevated.

Located in the feed pipe 8, at a point adjacent the operating rod, 14, is a valve, 19. A valve spindle, 20, extends outwardly from the valve in a direction substantially parallel to the rod, 14, and two arms, 21 and 22, secured to the body of the valve, extend therefrom one on each side of the spindle and in the same substantially horizontal plane. The arm 22 is rigid, and a slot 22^a is formed therein, as shown in Fig. 1, while the arm 21, is pivoted at its inner end to the valve body. A rod, 23, is pivoted at one end to the outer extremity of the arm 21, and also to the valve spindle, 20, and passes through the slot 22^a, in the arm 22. The outer extremity of the rod, 23, is forked, and vertical slots, 24, are formed in the two forks. The operating rod, 14, passes between the forks of the rod, 23, and pins, 25, carried by the operating rod extend into the slots, 24, and so form a sliding connection between the said operating rod, 14, and the rod 23. By means of this connection between the operating rod and the spindle of the valve, the openings and closings of the cap, 10, and of the valve are made to synchronize, and neither one can be opened or closed independently of the other. The rod, 23, is extended beyond the rod 14, and a bar, 26, secured at one end to the floor by means of a swivel attachment, 27, is adapted to be swung up and retained in vertical position, in which position it stands in the path of the said extension upon the rod 23; and thus, when the valve and cap are open and the rod 23 is in the position shown in dotted lines in Fig. 2, the bar, 26, being swung up acts as an additional and positive lock for the apparatus to retain the valve and cap in the open position until such time as it is desired to close them. A spring, 23^a, secured to both the bracket, 16, and to the rod 23, tends to close and keep closed the cap and valve. The bar 26, performs a further function of extending across the cover, 6, in which position it may be locked by means of a suitable clamp 28 upon the floor which engages the free extremity of the bar, the bar thus acting to fasten down the cover, 6, if this is necessary. The means for retaining the bar, 26, in vertical position comprises in the present instance an upstanding bracket 29, into which the said bar passes and to which it is held by a pin, 30, which is inserted in the bracket.

As illustrated in Fig. 1, a cavity, 31, is preferably formed in the side wall of the vessel at the point where the pipe 3, passes therethrough, whereby the end of the pipe and the cap are kept within the contour of the side and do not project. Stuffing boxes, 32 and 33, are located in the vessel wall through which the rod, 12, and the pipe, pass respectively, whereby the joints are rendered watertight. A nozzle, 34, connected with a

water line, extends into the interior of the pipe at a point near the outer end thereof and discharges directly through the open end of the pipe, ridding the surrounding area of the dust given off by the ashes.

70

In Fig. 6 I have illustrated a modification in which a closure, 10^b, is mounted within the pipe and swings up into a cavity formed in the pipe for its reception. The pivot bar, 10^c upon which the closure is mounted, extends through the side of the pipe, and has a lever arm 10^d to the outer end of which the rod, 12, is pivotally attached.

75

As the operating element of my ejector I prefer to employ compressed air. Upon 80 ocean going vessels it is a precept to conserve the supply of sweet water as much as possible, and for this reason condensers are employed with all of the engines. Where steam is used with ejectors of the type herein 85 described, this steam is a clear loss of sweet water besides constituting an extra drain upon the boilers. By the use of compressed air I am able to avoid this waste of sweet water, and am further able to operate the 90 compressing mechanism with a materially less expenditure of live steam, thereby greatly increasing the efficiency of the entire operation, as well as eliminating one of the 95 most objectionable features attached to the use of these ejectors in ocean going vessels.

A further fundamental objection to ejectors of this type in vessels employed in ocean travel, has been the fact that in heavy seas there would be continual danger of 100 water entering the interior of the vessel by way of the ejector pipe, and as a consequence of this possibility no underwriters could be found to subscribe to vessels supplied with this form of ejector. This objection I have 105 completely overcome by providing means for positively sealing the end of the pipe against the entrance of water.

The conservation of power being of prime necessity on vessels it is to be expected that 110 valve supplying fluid will be shut off after ashes have been discharged, especially as the operation of the valve is accompanied by plainly audible noises. Thus by interconnecting the operation of the valve and the cap at 115 the end of ejector, so that the latter closes down when the valve is shut off, it is assured, that the cap will be shut tight after discharge of the ashes has been completed. In addition to these devices for preventing 120 the entrance of water into the ejector pipe, secondary means is provided for preventing positively the entrance of water into the vessel by way of the pipe, these means consisting of the valve, 7, and the water tight cover, 125 6, with its clamping bar, 26.

These various devices though substantially fool proof are essentially simple, are easily installed, and are free from complicated parts and fixtures which might get out of 130

order. The general efficiency of ejectors of this type has been proved, as those acquainted with the art well know, and with the requirements of the underwriters fully met, 5 their value in the connection herein described will be realized.

I claim:

1. In an ejector, the combination with a conveyor duct having intake and discharge 10 openings therein, of a closure for said discharge opening, an operating rod for said closure, means for discharging a stream of fluid through said duct, a valve controlling the flow of said fluid, an operating rod for 15 said valve, interconnecting means between said closure and valve-operating rods whereby the opening and closing of said closure effects simultaneously and respectively the opening and closing of said valve, a closure 20 for said intake opening, a rod pivotally fixed at one end and adapted to lie across said intake closure to retain the closure in place, said rod when elevated to release said intake closure being adapted to engage said valve-operating rod to retain the said valve and 25 discharge closure in open position, and means when the said retaining rod is lowered to hold the said intake closure in position for automatically returning the discharge closure and valve to the closed positions.

2. In an ejector, the combination with a conveyor duct having intake and discharge 30 openings therein, of closures for said openings, operating means for said discharge closure, and locking means for said intake closure, said locking means when in unlocking position operating in conjunction with said discharge closure operating means

to retain the discharge closure in the open 40 position.

3. In an ejector, the combination with a conveyor duct having intake and discharge 45 openings therein, of means for discharging a stream of fluid through said duct, a valve controlling the flow of said fluid, closures for said intake and discharge openings, operating means for said discharge opening, operating means for said valve, said valve and closure-operating means being interconnected so that opening and closing of the discharge closure effects simultaneously and 50 respectively opening and closing of said valve, a locking device for said intake closure, said locking device when in the open 55 position engaging said closure and valve-operating means to retain the said valve and closure in open position, and means when the said locking device is returned to the locking position whereby said valve and closure 60 are closed.

4. In an ejector for ash and like material, the combination with an open-ended duct having an intake opening for said material intermediate the ends thereof, of a nozzle 65 projecting into the duct and adapted to direct a stream of fluid away from the intake opening toward the discharge end of the duct, a valve controlling the flow of fluid through the nozzle, closures for the open 70 ends of the duct and for said intake opening, and an interconnection between the valve and the closure at the discharge end of the duct such that the opening and closing of one entail respectively opening and 75 closing of the other.

EUGENE HAHN.
